UNITED STATES PATENT OFFICE.

ADOLPH TEUSCHER AND OTTO TEUSCHER, OF HILLSDALE, OREGON.

AUTOMOBILE-SANDER.

1,347,306.

Specification of Letters Patent. Patented July 20, 1920.

Application filed March 10, 1920. Serial No. 364,658.

To all whom it may concern:

Be it hereby known that we, ADOLPH TEUSCHER and Otto TEUSCHER, citizens of the United States, and residents of Hillsdale, county of Multnomah, and State of Oregon, have invented an Automobile-Sander, of which the following is a specification.

Our invention relates more particularly to self-propelled vehicles such as are used without rails, but is also applicable to trailers adapted to be drawn by such vehicles.

The object of our invention is to provide an exceedingly simple, efficient and inexpensive means for preventing slippage and skidding of automobile wheels.

We accomplish these results in the manner described in the specification following and illustrated in the accompanying drawing, in which:-

Figure 1 is a perspective diagrammatic view of the device showing its application to a truck. Fig. 2 is an enlarged elevation of a sand distributing valve mechanism. Fig. 3 is a sectional plane of Fig. 2. Fig. 4 is a detailed elevation of the lower end of the valve operating lever. Fig. 5 is an enlarged side elevation of the operating pedal.

Similar numbers of reference refer to the same or similar parts throughout the several views.

In this drawing we have illustrated the application of our device to a truck whose frame 7 and wheels are shown in dotted lines, and whose front portion is entirely cut away for clearness. We have constructed a double sand hopper 8 which branches out laterally in two directions, each portion of which terminates in a throat 9 which is secured to the inside of a hopper funnel 10 by means of the rivets 11. The lower portion 12 of the hopper funnel 10 is cylindrical in form and contains a butterfly valve 13 which is mounted on a shaft 14 which journals in the walls of the cylindrical portion 12.

An operating lever 15 is secured to the shaft 14 and has tapped into its outer end a screw-eye 16 which is held in correct adjustment by the lock nut 17. Distributing tubes 18 telescope over the outer portion of the member 12 and are secured to same by means of the slot 19 in the tube 18 which hooks over the pin 20 in the outside of the member 12. The lower end of the distributing tubes

18 is positioned to discharge sand in the track of the wheels 21.

The operating cables 22 are attached to the screw-eye 16. The springs 23 hold the butterfly valves 13 in the closed position 60 against the tension of the cables 22. These cables unite and are carried forward to the lower end of the brake pedal 24 and thence up through the brake pedal foot pad to an auxiliary toe pedal 25 which is hinged by 65 centrally located ears to the upper end of the foot pad by means of the eye bolts 27. The cable 22 passes over the required number of guide pulleys 28 to cause any forward action of the toe pedal 25 to produce 70 a pull on the cables 22, thereby opening the butterfly valve 13 at the same time and the same amount.

It will be seen that the sand 31 placed in the hoppers 8 can be distributed in the track 75 of both wheels at precisely the same time by regulating the position of the screw-eye 16.

Since it is a well known fact that vehicles equipped with tires without ground-gripping qualities are a constant source of danger to the public and property, and as it is known that the conditions most favorable for skidding is the time when the pavement has received its first moisture after a dry period, it will be seen that the average truck 85 wheel will usually be found without its ground-gripping appliances when most needed. Furthermore in attempting to negotiate a hill having a smooth pavement it is often found extremely difficult for trucks to 90 gain the incline without undue slippage and resulting strains on the working parts of the automobile. Furthermore in attempting to stop a car equipped with our device, it will be found that we have provided an excellent 95 medium for enabling the truck wheels to maintain their grip on the ground.

While we have thus illustrated and described our invention it is not our desire to limit ourselves to this precise form or 100 method of application, but intend that it shall cover all forms and modifications that fall fairly within the appended claims.

What we claim as new and desire to protect by Letters Patent of the United 105 States, is:

1. In a device for preventing the skidding of automobile wheels, the combination of a sand containing receptacle, delivery tubes adapted to carry the sand from said recep- 110

tacle to the wheel track, butterfly valves within said delivery tubes, spring return cables adapted to operate said butterfly valves, and a toe operated pedal mounted on 10 the brake pedal adapted to actuate said cables.

2. A mechanism for actuating a sand controlling valve of the character described, consisting of a toe pedal centrally pivoted

on the upper end of the brake pedal and 15 having a flexible cable attached to the lower and under side of said toe pedal which cable passes over a pulley of guide sheaves in a manner to exert a pull on the cable at the point of attachment to said controlling 20 mechanism.

ADOLPH TEUSCHER.
OTTO TEUSCHER.
